BOBBIN SUPPORT

Louis B. Hasbrouck, Elmira, N. Y., assignor to
 Eclipse Textile Devices, Inc., Elmira, N. Y., a
 corporation of New York

Application July 20, 1929, Serial No. 379,634

1 Claim. (Cl. 242—130)

This invention relates to bobbin supports, and aims to provide an improved means for mounting roving bobbins on the creels of spinning frames and the like.

5 The invention relates particularly to a bobbin support of the type shown in U. S. Patent No. 1,692,441, issued November 20, 1928 to my assignee, Eclipse Textile Devices, Inc., in which the bobbin is suspended by one end from a single bearing. In the device shown in that patent, the bearing is formed to serve at the same time as a universal joint, permitting a limited tipping of the bobbin. In accordance with my present invention, the bobbin is suspended from a bearing and a separate joint which permits unlimited tipping thereof in all directions.

In my aforesaid patent, the bobbin was gripped directly by the rotary member of the bobbin support and was used without a skewer, so that some 20 change in the habits of the operatives was required. In accordance with the present invention this inconvenience is avoided by providing for supporting the bobbin on a skewer. At the same time, the irregular friction caused by the 25 ordinary skewer mounting is avoided, and the advantages of a suspended mounting are secured.

In order that the invention may be clearly understood, I will describe in detail specific embodiments of it, which are shown in the accompanying drawing in which:

30 Fig. 1 is a transverse sectional elevation of the upper part of a spinning frame of usual construction, showing the creel provided with bobbin supports embodying the invention; and

35 Fig. 2 is an enlarged axial section of one of the bobbin supports shown in Fig. 1.

The bobbin support illustrated includes a fixed supporting member 10 secured to one of the creel-boards C, and a rotary member 12 connected to the fixed member 10 by a single bearing 11. The 40 fixed and rotary members 10 and 12 are provided with opposed bearing surfaces 13 and 14, which serve as races for bearing balls 15 inter-

posed between them. It is desirable, but not essential, to make one of the bearing surfaces, for example, the surface 13, spherically curved as in my aforesaid patent.

The rotary member 12 is very short, and has 60 secured to its bottom a hook 16 from which is suspended an eye 17 secured in the upper end of a skewer S carrying a bobbin B. The skewer S differs from the ordinary skewer only in that the projecting upper end of such a skewer, which ordinarily enters a socket in the upper creel-board, is replaced by the eye 17. The skewer S is suspended with its lower end clear of the creel-board C1 below it, instead of with its lower end in a cup on this creel shown as in the usual skewer 70 mounting.

The hook and eye 16 and 17 provide an articulated joint which permits the bobbin to hang with its center of gravity directly below its point of support, regardless of a lack of symmetry in 75 the winding of the roving or a lack of accuracy in the attachment of the fixed member 10 to the creel-board. This fact, coupled with the fact that the lower end of the skewer and bobbin are entirely free, makes the rotational resistance 80 very slight and perfectly even as the roving is drawn off the bobbin.

Operatives may replace the bobbins without any change in their habits, since the up and down motion required to hook or unhook the eye of 85 the skewer is the same as that required to place a skewer in the ordinary socket and cup mounting.

What I claim is:

A bobbin support for the creels of spinning 90 frames, comprising a fixed member, a rotary member, a bearing between the fixed and rotary members formed to permit the rotary member to tip with respect to the fixed member, and a hook and eye connecting a bobbin to the rotary 95 member and permitting the bobbin to tip with respect to the rotary member.

LOUIS B. HASBROUCK.
